UNITED STATES PATENT OFFICE.

EDMUND H. LUNKEN, OF CINCINNATI, OHIO.

SCREEN DEVICE FOR POCKET-WINDOWS.

1,259,113.

Specification of Letters Patent. Patented Mar. 12, 1918.

Application filed February 12, 1917. Serial No. 148,080.

To all whom it may concern:

Be it known that I, EDMUND H. LUNKEN, a citizen of the United States, and a resident of Cincinnati, in the county of Hamilton 5 and State of Ohio, have invented certain new and useful Improvements in Screen Devices for Pocket-Windows, of which the following is a full, clear, and exact description, reference being had to the accompanying drawings, forming part of this specification.

My invention relates to screens for pocket windows and has for its object the provision of a complete and fully adequate screening 15 for sliding sash pocket windows having a wall pocket wherein the screens may be concealed.

One of the important advantages resulting from the use of pockets for windows 20 is that window screens may be kept permanently in the windows and moved into the window pockets both to get them out of the way and for winter storage. The difficulties to be met with in providing for this 25 advantage are several, however. In the first place, there has not been developed, to my knowledge, in the past, a proper method of installing sliding screens in such windows which permits of their easy setting up and 30 removal. In the next place no proper weather seal has been provided between the window sash, the screens and the pocket walls, which is very important since without such devices there is always the possibility 35 of draft getting into the room by circulating around in the pocket, past the screen opening and down along the sash of the window.

It is the object of this invention to provide 40 against the above disadvantages, and the said objects now mentioned and other advantages to be noted are accomplished by that certain construction and arrangement 45 of parts to be hereinafter more specifically pointed out and claimed, wherein particularly the supporting rails for the screen channel guides are set in place in the windows after the pockets have been formed and are easily removable in one piece.

50 In the drawings,

Figure 1 is a central vertical section through a window showing the screening devices.

Fig. 2 is a cross section on the line 2, 2, 55 of Fig. 1.

Fig. 3 is a detail perspective view of the arrangements of guides for the screens.

Fig. 4 is a detail perspective view illustrating the method of removing the lower screen from said guides or channels, on a 60 larger scale than Fig. 3.

Fig. 5 is a detail vertical section of the window showing the lower ends of both screen members when raised into the pocket as for winter storage. 65

Fig. 6 is a detail perspective view of the upper corner of the top screen showing the top strip thereon.

Fig. 7 is a detail perspective view showing the channel arrangement and the stop 70 lug for the upper screen.

Fig. 8 is a perspective of the removable channel piece.

Fig. 9 is a detail perspective showing the manner of setting the screen guides in the 75 pocket.

The pocket window has the upper and lower sliding sashes 1 and 2 respectively, which sashes slide on the stiles 3, which are provided with the parting rails 4, inner 80 guide rails 5, and outer guide rails 6. On the outer guide rails 6 are to be mounted the screen channels and these outer guide rails (one on each stile of the window), run with the stiles up into the pocket 7 formed 85 in the walls 8 above the window opening. So far as the screen channel members are concerned and the method of mounting the supporting rails therefor, this function of the guide rails 6 in serving to guide the 90 sashes is not an absolute requisite, as the sash guide might be a separate member. Between the wall pocket and the interior of the building, there is the usual plastered 95 wall 9, and the window frame is shown with the usual cap trim 10, base trim 11 and sill 11a. The plastered wall I prefer to construct with corrugated metal lath 9a, which gives sufficient rigidity to the wall.

Secured to the top of each sash in the 100 usual way, are the cords 12, which are led up to pulleys 13 in the top of the wall pockets. The arrangement of pulleys and the method of counterbalancing the sash while permitting it to ride up to the top of the 105 pocket is shown and described fully in my Patent No. 1,201,598, dated October 17, 1916, to which patent reference is hereby made.

On the outer guide rail 6 for the sash, as 110

above stated, are mounted the channel guides for the two screens, there being a lower screen 17 and an upper screen 18. It is preferred to make up these guide channels in two different sections. Extending up from the base of the guide rail 6 on each side, is the lower channel section 16 (Fig. 3), which is of a size to accommodate only the lower screen member 17. This lower section extends up approximately to the center line of the window.

The top channel member 19 is set on the guide rail 6 and mounted in the window frame with this guide rail as will be noted.

15 It is of a size double that of the lower channel member, and thus is adapted to slidably receive both screen members. This channel member extends to meet the lower section and is cut away at 21 to leave space for a 20 removable insert 22 which when screwed or otherwise secured against the guide rail completes the channel member 19 and forms of it a double width channel throughout.

25 The removable piece 22 is in the form of an angle, and is adapted to extend beyond the lower edge of the top section and past the upper edge of the lower section. Set into the portion of the piece 22 which so extends, is a lug 23 which extends in such a 30 way as to close off the one half of the channel flush with the top of the lower channel member. This lug thus serves as a stop for the upper screen member, and may be of one piece with piece 22 or screwed down as 35 shown.

40 The piece 22 has its side wall bent outwardly at 24 so as to lap over the cut away edge of the side wall of the upper channel section, thereby forming a flush inner wall for the combined members against which the upper screen will not be likely to catch. There is sufficient length to the portion 24 to allow for adjusting the position of the piece 22 and hence the lug 23 thereon, or else 45 the lug 23 may be positioned and the holes drilled for it after placing the piece 22.

As so constructed, the channels serve to slidably mount the screens throughout the length of the window opening and pocket, 50 and as will be described the removable piece 22 is all that need be taken off of the channel guides to permit both screens to be removed.

55 In mounting the channel members for the screens, they are first secured, all but the piece 22, to the rail 6. The rail 6 is then mounted in the window after the pocket has been completed, and as will be understood can be readily dismounted and remounted 60 again without difficulty. In forming the top of the pocket, the top board 6^a of the pocket is cut away at 6^b adjacent the side stiles of the frame, which extend up to this top board. This cut 6^a is sufficient to allow 65 the rail 6 with the channel members thereon

to be tipped up into the pocket, and pushed into the socket, the channel being cut away. Several screws beneath the pocket, or as far in the pocket as can be reached easily, serve to hold the rail in place.

70 It will be understood that by removing the screws, the rail may be tipped and drawn out, and also that it is not absolutely essential that the rail be in one piece except so far as it extends into the pocket. The 75 spirit of the invention is intended to cover the making of this rail in several pieces, although it is not believed that this would be done in any practical structure.

80 The screens as shown are made up of moldings 25, across which are suitably stretched and held the screen wire. On the lower molding of the lower screen is mounted a depending angle piece 27, and at each corner of it are mounted the housings 27^a 85 for the sliding bolts or pins 28. Suitable sockets 29 for these pins are formed in the lower end of the side guide rails 6, and also at any other point along the rails, such as at 30 in the channel member just beneath the 90 wall pocket opening, where it is desired to hold the screens. When the bolts are thrown in at 30, they will tend to close the space left in the channel by the upper screen, and for this reason should be made of sufficient 95 width to fulfil this function as much as possible. The angle piece rests on the sill and permits a finger hold on the lower screen molding. Also fingers 28^a for the locking bolts project inwardly in the space beneath 100 the lower molding of the screen, so as to be readily available passing through a slot in the angle plate. The piece 23 is beveled at 22^a to strike out the bolts 28 on raising the screen.

105 The lower screen member has at the outside of its upper molding a strip 31, which extends so as to contact with the upper side of the lower molding of the upper screen, and thereby form a complete insect proof 110 joint. When the lower screen is raised, this strip 31 strikes the upper molding of the upper screen and moves it upwardly also. When the lower screen is pulled down this strip strikes the lower molding of the upper 115 screen and pulls it down also, if it should happen to stick in the pocket.

120 The upper screen has an angle piece 32, set over its top molding, which piece 32 when added to the top molding makes it of the size of the double width channel, so that it will slide and be guided therein. This piece extends into the path of the top molding of the lower screen so that a wide contact is provided between the moldings of the 125 upper and lower screens, since it will be remembered that the strip 31 on the lower screen also acted as a contact member. The size and position of the piece 32 can be regulated.

The top rail of the upper sash has set into it a weather strip 32^a. This is preferably done by mounting the strip together with a molding 33 on the top of the sash rail. The 5 weather strip extends rearwardly and the parts are proportioned so that the strip will contact with the lower molding of the lower screen when said lower screen is in the wall pocket, and also so that it will contact with 10 the upper molding of the upper screen as filled out by the angle strip hitherto described when the upper screen is down.

Thus when the screens are stored for the winter, in the pocket, there will be a weather 15 seal between them and the sash, and the weather seal will also be provided for when the screens are down and in use.

Set into the lower end of the outside trim of the window frame by means of a suitable 20 molding strip 34, is another weather strip 35 which is adapted to contact with the upper molding of the upper screen when down, and the angle piece depending from the lower screen is proportioned so that it 25 will lie along the under side of the molding 34. So no matter whether the screens are up or down, dust cannot circulate past the screens, up into the pocket and thence into the interior of a building through the pocket 30 opening for the lower sash.

The depending angle strip on the lower screen is wide enough to just clear the channels and long enough to bring the meeting rails of the screens adjacent the meeting 35 rails of the sash. This is because the standard lower sash is usually longer than the upper, and to balance the screen structure it would otherwise be necessary to have screens of different size, which is avoided by 40 the use of this depending strip. This positioning of the meeting rails of the screens is but one of the valuable results of the use of this depending strip since it also permits the upper molding of the upper screen to 45 partially lie in the pocket, thereby forming a weather seal as above described. This angle strip and the other projecting strips are to be screwed into place on the screens so as to be removable for installation on 50 replaced screens in case of repairs, so that the provision of screens for this structure becomes an easy matter since only standard screens of equal size need be obtained, and the molding attachments made by the in- 55 stalling contractor.

In putting up the screens, the rails are tipped into place and screwed down, with the channels on them as described. The lower screen is then slipped into place 60 through the opening left for the piece 22, and dropped down in the channel member 16. The upper screen is then slipped in, and the lower screen slightly raised, so that its upper projecting strip will be caught 65 above the lower molding of the upper screen,

and both screens are pushed up into the socket until they lie above the opening for the piece 22. The piece 22 is then set in place, and positioned so that when the upper screen molding lies partly in the pocket, the 70 depending angle strip on the lower screen will seat on the sill of the window. It is sometimes necessary to shift the lug 23 and drill the hole for it in piece 22 after the screens have been tried. Thus it can be seen 75 that screens are provided which will easily slide up into the pocket of a window, without leaving any dust entrance into the pocket through the opening for the screen.

To prevent the dropping of the screens 80 in the channels and to avoid the necessity of placing springs on the screens as is the customary practice, the channels are fitted with springs as follows:—Alongside of the insert 22 of the channels is set the spring 40, and 85 above it and in the insert itself is placed the spring 41. These two springs take up the jar which would result from the sudden dropping of the screens from the pocket, and springs 41 act as a protector against the 90 bolts 28, as does the beveled face of the lug 22.

Also it is plain that screen channel guides are provided which can be set into pocket windows and removed and replaced without 95 difficulty, these guides being mounted preferably on the outer sash guide rail, thereby narrowing the necessary width of the pocket. If desired, some method of counterbalancing the screens could be provided for, although 100 this is not insisted upon.

The various details of the above structure could readily be modified without departing from the spirit of the invention herein, and it is not desired that limitations of the 105 claims be implied because of failure to mention such equivalent structural modifications, nor is it desired that this invention be limited to the mounting of wire screens only, since blinds or shutters for screening or 110 shading purposes could be mounted in the same manner.

Having thus described my invention, what I claim as new and desire to secure by Letters Patent, is:—

1. In combination with a window frame having a wall pocket at one end thereof, channel guide elements for screen or shutter members, said elements being adapted to extend the length of the window frame and 120 pocket, and means for demountably securing one end of the elements in the end of the pocket away from the opening of the frame, and for securing the elements at another point within the frame opening.

2. In combination with a window frame having a wall pocket at one end thereof, channel guide elements for screen or shutter members, said elements adapted in one piece to extend the length of the frame and 130

pocket, and adapted to be demountably held at the closed end of the pocket, and secured to the window frame by means within reach in the opening thereof.

- 5 3. In combination with a window frame having a wall pocket at one end thereof, channel guide elements for screen or shutter members, said elements adapted in one piece to extend the length of the frame and pocket, and adapted to be demountably held at the closed end of the pocket, and secured to the window frame by means within reach in the opening thereof, a sliding sash in the window frame, with said channel guide elements to serve as an outer guide rail for said sash.
- 10 4. In a screening device for pocket windows, the combination with a window frame having an opening and a wall pocket at one end thereof, a plurality of sliding screens mounted to slide in said frame into the said pocket, said screens being arranged such that when the upper edge of the upper screen lies within the pocket opening, the lower edge 25 of the lower screen is against the sill, and the meeting edges of the screens interlock.

5. In a screening device for pocket windows, the combination with a window frame having an opening and a wall pocket at one end thereof, a sliding sash in the window, a sliding screen in the window independent of the sash, both screen and sash being mounted to slide into the pocket, and weather sealing devices between the portions of the frames of the screen and of the sash which lie at the entrance to the pocket when in normal closed position.

6. In a screening device for pocket windows, the combination with a window frame having an opening and a wall pocket at one end thereof, a sliding sash in the window, a sliding screen in the window, both screen and sash being mounted to slide into the pocket independent of each other, and 45 weather sealing devices between the portions of the frame of the screen and the frame of the sash that lie at the entrance to the pocket when in normal closed position, said screen having likewise weather sealing 50 means between the outside of the frame thereof and the wall of the pocket.

7. In combination with a window frame having a wall pocket, a sash adapted to slide into the pocket, an outer guide rail for said sash, screen channel pieces mounted on said guide rail, means for detachably securing one end of the guide rail in the closed end of the pocket, said guide rail and channels extending the length of the window frame and 60 pocket.

8. In combination with a window frame having a wall pocket, a sash adapted to slide into the pocket, an outer guide rail for said sash, screen channel pieces mounted on said 65 guide rail, means for detachably securing

one end of the guide rail in the closed end of the pocket comprising a socket in the said end of the pocket into which the rail may be tipped.

9. In a pocket window, the combination 70 with an upper and lower screen member, of a channel formation adapted to permit the screens to slide into the pocket and to guide said screens, comprising a single width channel member for the lower screen, positioned 75 to retain said screen in its lowered position, and a double width channel member extending toward and into the pocket from the first channel, and adapted to receive and guide both screens.

10. In combination with the outer guide rail for a window sash, said guide rail adapted to extend the length of a window opening and wall pocket, a screen guiding device on the rail and adapted to be inserted 85 in the window and removed in one piece with the guide rail.

11. In a screen device for pocket windows, upper and lower sliding screens adapted to slide entirely into the pocket, sliding sashes 90 in the window adapted also to slide into the pocket, a double width guide to accommodate both screens in the pocket, and a detachable element on the upper screen molding 95 ing to fill the double channel.

12. In a screen device for pocket windows, the combination, with two sliding screen members, of a projecting strip extending across the lower screen to contact with the moldings of the upper screen, said screens 100 set so that the said means lies between the upper and lower moldings of the upper screen and contacts with both of said moldings, for the purpose described.

13. In a screening device for pocket windows, the combination with a window frame and pocket extending above it, and sliding sashes therein, of an upper and lower screen member independent of the sashes, said lower screen adapted to contact with the outer wall of the pocket when up, the upper screen adapted to contact with the outer wall of the pocket when down, and contact means between the upper sash and the screens when in either of the positions 115 now mentioned.

14. In a screening device for pocket windows, the combination with a window frame and pocket above it, and sliding sashes therein, of two screen members independent 120 of the sashes and of equal size for screening said window, said screens having molding attachments thereon adapted to bring the meeting rails of the screens above the median line of the window, the upper end of 125 the upper screen within the pocket opening, and the lower end of the lower screen against the sill of said window frame.

15. In a screening device for pocket windows, the combination with a window frame 130

- and pocket above it, and sliding sashes therein, of two screen members independent of the sashes and of equal size for screening said window, said screens having molding attachments thereon adapted to bring the meeting rails of the screens above the median line of the window, the upper end of the upper screen within the pocket opening, and the lower end of the lower screen 10 against the sill of said window frame, said attachments comprising in part a depending strip on the lower screen, said strip thereby holding the lower screen molding off the sill for providing a finger hold.
- 15 16. In a pocket window, the combination with an upper and lower screen member, of a channel formation adapted to permit the screens to slide into the pocket and to guide said screens, comprising a single width channel member for the lower screen, positioned to retain said screen in its lowered position, and a double width channel member extending toward and into the pocket from the first channel, and adapted to receive and guide 20 both screens, and springs set in the channel structures adjacent the end of the double channel, one for each screen.
17. In a screening guiding device for pocket windows, a half width channel the 30 length of a lower screen, a double width channel extending up into the pocket for both screens, a removable piece in the double width channel for inserting the screens, and a lug closing said removable piece and serving as a stop for an upper screen.
- 35 18. In a screening guiding device for pocket windows, a half width channel the length of a lower screen, a double width channel extending up into the pocket for both screens, a removable piece in the double width channel for inserting the screens, and a lug closing said removable piece and serving as a stop for an upper screen, a locking bolt for the lower screen, 40 said lug being beveled on its lower face to prevent its catching on the bolt.
- 45 19. In a pocket window, the combination with a frame having an overhead pocket, a sliding sash in the pocket, and means for providing a weathering on the outer side 50 of the upper rail of said sash for contact with screens or the like, comprising a molding mounted on the top of the upper rail and a compressible strip held between the molding and the upper rail, said strip extending outwardly from the sash to provide such weathering.
- 55 20. In a pocket window, the combination with a window frame and wall pocket, of a sliding sash in said window, adapted to slide freely into the pocket, a weathering member on that portion of the sash that lies at the mouth of the pocket when in normal closed position, and a member located against the outer wall of the pocket at the 60 mouth thereof and projecting inwardly so as to contact with the said weathering, whereby the said window is sealed from the outside air.
- 65 21. In a pocket window, the combination with the frame and pocket thereof, of a plurality of sashes in the window, each adapted to slide into the pocket, and means for sealing the window from the outer air comprising a member projecting inwardly from the 70 outer pocket wall at the mouth thereof, and a member located on the upper side of the upper sash rail, and projecting outwardly therefrom, said member being adapted to contact with the inwardly projecting member 75 when the upper sash is in normal position, said projecting member on the sash adapted to pass in either direction the other projecting member.
- 80 22. In a pocket window, the combination with a frame having an overhead pocket, a sliding sash in the pocket, and means for providing a weathering on the outer side of the upper rail of said sash for contact with a member projecting inwardly from the 85 mouth of such pocket, comprising a molding mounted on the top of the upper rail and a compressible strip held between the molding and the upper rail, said strip extending outwardly from the sash to provide 90 such weathering.
